UNITED STATES PATENT OFFICE.

BENJAMIN E. ROBINSON AND ROBERT A. TROBAUGH, OF TULSA, OKLAHOMA.

COMBINATION GEAR AND WHEEL PULLER.

Application filed May 8, 1925. Serial No. 28,923.

To all whom it may concern:

Be it known that we, BENJAMIN E. ROBINSON and ROBERT A. TROBAUGH, citizens of the United States, residing in the city and county of Tulsa and State of Oklahoma, have invented certain new and useful Improvements in Combination Gears and Wheel Pullers, of which the following is a specification.

This invention relates to a tool or implement known generally as a wheel puller, but it is to be understood that this term is not used in its restrictive sense, because the device is capable of utility for purposes other than conveyed by the expression, and the object of the invention is to provide, in a manner as hereinafter set forth, a device of the character referred to, with means for removing wheels, gears, spindles, etc., and which will be as nearly universal as possible in respect to application of objects or elements of this nature of different shapes, sizes and construction.

A further object of the invention is to provide, in a manner as hereinafter set forth, a device of the character referred to, with a plurality of removable clamping elements which can be readily replaced when worn.

Further objects of the invention are to provide, in a manner as hereinafter set forth, a tool or implement of the character referred to, which is simple in its construction and arrangement, strong, durable, compact, thoroughly efficient and convenient in its use, readily set up, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts, throughout the several views:

Figure 1 is a section on line 1—1, Figure 2.

Figure 2 is a front elevation of a tool or implement in accordance with this invention.

Figure 3 is a perspective of a hub clamping element.

Figure 4 is a fragmentary view of the body portion of the tool or implement provided with a gear clamping element, the latter being shown in section.

Figure 5 is a section on line 5—5, Figure 4.

Figure 6 is a fragmentary view of the body portion of the tool or implement provided with a radius increasing attachment carrying a gear clamping element.

Figure 7 is a fragmentary view of the body portion of the tool or implement illustrating a modified form of gear clamping means.

Referring to the drawings in detail, 1 denotes a cylindrical tapering head piece, having formed integral with the end of larger diameter thereof four pair of substantially triangular-shaped arms. The arms of one pair are indicated at 2, 3, the arms of another pair at 4, 5, the arms of another pair at 6, 7, and the arms of the remaining pair at 8, 9. The pairs of arms are radially disposed with respect to the head piece 1, and the arms of each pair are spaced from each other. The outer corners at the forward ends of the arms 2, 3, merge respectively in the outer corners of the forward ends of the arms 9, 4, as at 10, 11. The outer corners at the forward ends of the arms 5, 8, merge respectively in the outer corners of the forward ends of the arms 6, 7, as at 12, 13. The forward ends of each of said arms are of greater width than the rear ends thereof and the outer edges of said arms form continuations of the outer periphery of the head piece 1.

The inner side of each of said arms, at its forward end, is formed with a rib 14 of a length equal to the width of the arm at the said end, and said rib 14 forms a shoulder 15. The ribs of each pair of arms oppose each other. The ribs of each pair of arms provide a pair of combined guides and retainers for a clamping element to be presently referred to. The forward end of each of the arms, at the outer side thereof, is provided with an extension 16 of materially less width than the width of said end.

Formed integral with the forward end of each pair of arms, at the outer portion thereof, and extended forwardly therefrom is an apertured boss having the wall of its opening threaded. The said bosses are disposed at right angles with respect to the forward

edges of said arms, and the boss formed integral with the arms 2, 3 is indicated at 17, that formed integral with the arms 4, 5, at 18, that formed integral with the arms 6, 7 at 19, and that formed integral with the arms 8, 9 at 20. The opening formed in each of said bosses is indicated at 21. The outer side of each boss is flush with the outer edge of that pair of arms with which it is formed integral. The extensions 16 of the arms are formed integral with the bosses and project inwardly therefrom. The extensions are of less height than the height of the bosses.

15 The bosses are connected together by a series of inclined brace members 22, 23, 24 and 25 and said brace members are formed integral with the extensions 16 and the sides of the bosses. The brace member 22 is arranged between the bosses 17, 18, the brace member 23 between the bosses 18, 19, the brace member 24 between the bosses 19 and 20, and the brace member 25 between the bosses 20 and 17.

25 The head piece 1 is formed with a centrally disposed opening 26 having the wall thereof threaded, and extending through the opening 26 and threadedly engaging with the wall thereof is a forcing element having a plane cylindrical inner end 27 formed with an entering point 28, centrally thereof, and which projects forwardly therefrom. The forcing element further includes an intermediate peripherally threaded portion 29 and a rear end portion 30 having a part thereof of polygonal contour, as indicated at 31, for the reception of a suitable tool or implement for adjusting the forcing element.

35 Threadedly engaging with each of the bosses is an adjusting member 32 formed with a peripherally grooved inner end portion 33, a peripherally threaded intermediate portion 34 and a polygonal-shaped head 35. The inner portion 33 provides means for detachably connecting a clamping element to the adjusting member.

45 In Figures 1 and 2 of the drawings, each of the adjusting members has detachably connected therewith a hub clamping element 50 and which consists of an arcuate body portion 36, having its working face threaded, as at 37, and its back formed with a pair of oppositely disposed angle-shaped flanges 38, 39. Extended from the body portion 36 is a 55 T-shaped projection 40. The flanges 38 and 39 provide means for connecting the clamping element to the inner end portion of an adjusting member, and the extension 40 provides means for slidably connecting the 60 clamping element to the ribs of a pair of arms when the clamping element is shifted by an adjusting member. In Figure 1 of the drawings, a pair of hub clamping members 65 is illustrated in clamping engagement with the hub 41 of a wheel mounted on a

spindle 42, and with the entering point 28 of the forcing member seated in the end of the spindle.

The adjusting members provide means whereby the hub clamping elements can be 70 employed with hubs of varying diameters.

When the hub clamping elements are positioned in clamping engagement with the hub 41, the forcing member is adjusted inwardly and such movement will provide for 75 the pulling off of the hub 41 from the spindle 42. In Figures 4 and 5 of the drawings, there is illustrated a gear clamping element and when employed, the clamping elements are removed.

80 The gear clamping element consists of an interiorly threaded socket forming member 43 peripherally grooved, as at 44, for the reception of a pair of opposed ribs 14. Threadedly engaging with the member 43 is an adjusting bar 45 carrying a right angularly disposed gripping finger 46. The bar 45 is adjustable relative to the member 43 and is secured in adjusted position by a lock nut 47 carried thereby.

85 Figure 6 illustrates an attachment for extending the range of the puller beyond the radius of the bosses, and said device comprises an arm 48 bifurcated at 49 and shouldered, as at 50, and which provides means for connecting a clamping element therewith. The arm 48 is formed with a T-shaped extension 51, adapted to be connected with a 90 pair of arms through the medium of the ribs 14. When the attachment is in position, the extension 51 abuts against the boss as shown in Figure 6, and the clamping element carried by the arm 48 and which is indicated at 52, is arranged exteriorly of and spaced from 95 a boss.

100 For pulling off timing gears that cannot be reached by a gear clamping element, and with such gears having an opening formed with threaded walls for the purpose of attaching bolts therewith to pull the gears, a block 53 and a headed bolt 54 are employed. The block 53 is positioned against a pair of ribs 14 and the bolt 54 extended through the block and the arms with which the ribs are 105 formed integral, and the bolt 54 is then secured in the aperture 55 of the timing gear 56.

110 After the clamping elements have been mounted in position, whether said elements be employed for removing automobile or other wheels, the forcing element is operated and which acting in connection with the clamping elements will pull off the wheel.

115 The head piece 1, pairs of arms, bosses and brace members provide what may be termed a case, and the same can be of any polygonal contour, preferably square, but when square, four clamping elements will be employed, but if the case is hexagonal or octagonal, the number of clamping elements will be 120 125 130

increased, depending on the number of sides of the main case. When removing truck wheels or for larger gears, preferably the main case will be hexagonal or octagonal in 5 contour.

The threaded hub clamping elements will be constructed of varying sizes and with any number of threads to the inch as will suit the different requirements. The inner ends 10 of the adjusting members will be constructed in any suitable manner to connect with the clamping elements to adjust the same, but the connection will be such as to allow the adjusting members to rotate when shifting a clamping element. The reduced part 15 on the outer end of the forcing member is placed there for the purpose of striking with a hammer or sledge. A strong tension is had on the forcing member and in cases 20 where the wheel or gear is exceptionally difficult to remove, a blow with the hammer on this reduced part will help to break the bond between the axle and hub. The forcing member is to be threaded any style, such 25 as buttress, V, square, acme, etc., and any number to the inch as may be required by the nature of the work to be performed. The entering point on the inner end of the forcing member is for centering it on the 30 end of the spindle or axle and fits in the lathe center placed there for the purpose of machining the axle in manufacture.

It is thought that the many advantages of a tool or implement, in accordance with this 35 invention, and for the purpose set forth, can be readily understood, and although the preferred embodiment of the invention is as illustrated and described, yet it is to be understood that changes in the details of construction can be had which will fall within 40 the scope of the invention as claimed.

What we claim is:—

1. A pulling device comprising a main case consisting of an interiorly threaded 45 head piece, a plurality of spaced pairs of arms formed integral therewith and projecting forwardly therefrom, the arms of each pair arranged in spaced relation and each having the inner side of its forward end 50 formed with a rib, an interiorly threaded boss formed integral with the forward end of each pair of arms at the outer portion thereof and disposed at right angles with respect to the forward edge of said arms, 55 clamping means engaging the ribs of each pair of arms, and a forcing member adjustably engaging with said head piece and co-acting with said clamping means.

2. A pulling device comprising a main case 60 consisting of an interiorly threaded head piece, a plurality of spaced pairs of arms formed integral therewith and projecting forwardly therefrom, the arms of each pair arranged in spaced relation and each hav-

ing the inner side of its forward end formed 65 with a rib, an interiorly threaded boss formed integral with the forward end of each pair of arms at the outer portion thereof and disposed at right angles with respect to the forward edge of said arms, clamping means engaging the ribs of each pair of arms, a forcing member adjustably engaging with said head piece and co-acting with said clamping means, and adjusting members 70 mounted in said bosses for said clamping means.

3. A pulling device comprising a main case consisting of an interiorly threaded head piece, a plurality of spaced pairs of arms formed integral therewith and projecting forwardly therefrom, the arms of each pair arranged in spaced relation and each having the inner side of its forward end formed with a rib, an interiorly threaded boss formed integral with the forward end of each pair of arms at the outer portion thereof and disposed at right angles with respect to the forward edge of 80 said arms, clamping means engaging the ribs of each pair of arms, a forcing member adjustably engaging with said head piece and co-acting with said clamping means, each of the arms of each pair merging into 85 an arm of an adjacent pair, and brace members for connecting said bosses together. 90

4. A pulling device comprising a main case consisting of an interiorly threaded head piece, a plurality of spaced pairs of arms formed integral therewith and projecting forwardly therefrom, the arms of each pair arranged in spaced relation and each having the inner side of its forward end formed with a rib, an interiorly threaded boss formed integral with the forward end of each pair of arms at the outer portion thereof and disposed at right angles with respect to the forward edge of said arms, clamping means engaging the ribs of each pair of arms, a forcing member adjustably engaging with said head piece and co-acting with said clamping means, each of the arms of each pair merging into an arm 100 of an adjacent pair, brace members for connecting said bosses together, and adjusting members carried by said bosses for said 105 clamping means.

5. A pulling device comprising a clamping element, adjusting means therefor, a case consisting of an interiorly threaded head piece, a plurality of pairs of arms formed integral therewith and projecting forwardly therefrom, the arms of each pair having their forward ends provided with opposed means for slidably connecting the clamping element therewith, means formed integral with each pair of arms at the forward end thereof and disposed at right angles with respect thereto for connecting 110 115 120 125

therewith the adjusting means for the clamping element, and a forcing element threadedly engaging with said head piece.

6. A pulling device comprising a clamping element, adjusting means therefor, a case consisting of an interiorly threaded head piece, a plurality of pairs of arms formed integral therewith and projecting forwardly therefrom, the arms of each pair having their forward ends provided with opposed means for slidably connecting the clamping element therewith, means formed integral with each pair of arms at the forward end thereof and disposed at right angles with respect thereto for connecting therewith the adjusting means for the clamping element, and a forcing element threadedly engaging with said head piece and provided with a centering means at its inner end.

7. A pulling device comprising a clamping element, an adjusting member therefor, a forcing element, a case consisting of a

head piece formed with an opening having a threaded wall, a plurality of spaced pairs of arms formed integral with and projecting forwardly from said head piece, the arms of each pair arranged in spaced relation and having their inner sides provided with means for slidably connecting the clamping element therewith, each of the arms of one pair merging into an arm of an adjacent pair, the arms of one pair disposed at an angle with respect to the arms of an adjacent pair, an interiorly threaded boss formed integral with the forward end of each pair of arms and extending at right angles with respect thereto and providing means for connecting therewith the adjusting member for the clamping element, and said head piece providing means for threadedly connecting therewith the forcing element.

In testimony whereof, we affix our signatures hereto.

BENJAMIN E. ROBINSON.
ROBERT A. TROBAUGH.
